FURNACE STRUCTURE

Francis H. Brown, Ridley Park, Pa., assignor to
The Real Estate-Land Title and Trust Com-
pany, Philadelphia, Pa., a corporation of Penn-
sylvania

Original application December 21, 1922, Serial
No. 608,228. Divided and this application
October 22, 1934, Serial No. 749,433

6 Claims. (Cl. 110—35)

This invention is a division of my co-pending application S. N. 608,228, now Patent No. 1,977,-
620, and relates broadly to conveying and dis-
tributing material, and more particularly per-
tains to improvements in method of and appa-
ratus for feeding solid fuel, such as coal and the
like, to furnaces, such apparatus being commonly
known as stokers.

While this invention is illustrated as embodied
in an automatic stoking device for the purpose
of delivering and distributing fuel in a furnace,
whereby to increase the efficiency and the utility
of the furnace, it will be readily understood that
the invention is not limited to such an adapta-
tion, but finds a wide field of utility for other
purposes.

Among the more important objects and advan-
tages which characterize this invention, are: the
provision of an improved apparatus for conveying
and distributing fuel, such as coal and the like;
delivering fuel to a furnace and for distributing
the fuel evenly in the furnace; the provision of an
improved grate structure for furnaces and the
like.

It is an important object of this invention to
provide an improved mechanism for sizing and
evenly and uniformly distributing the fuel deliv-
ered to a furnace, and to this end the invention
involves an improved grate bar structure which
is characterized by the provision of a grate bar
comprising a perforated tube; the provision of a
grate bar provided with a plurality of radial ap-
ertures; the provision of a series of adjacent hollow
perforated grate bars; the provision of an im-
proved form of revolving grate bar; the provision
of a furnace structure characterized by the pro-
vision of revoluble grate bars; the provision of
groups of revoluble grate bars; the provision of
groups of revoluble grate bars for distributing
fuel through the furnace; the provision of a grate
bar structure which operates to deliver and
distribute fuel to a desired point for consumption
and during consumption in a furnace, and for
collecting and disposing of ash as formed; the
provision of an improved form of grate bar pro-
vided with a plurality of series of radially disposed
apertures; the provision of an improved revoluble
grate bar comprising a cylindrical shell or tube
provided with a plurality of circumferential series
of radial openings; and the provision, in a fur-
nace grate, of a series of parallel perforated
revoluble grate bars adapted to rotate in the
same direction and at the same speed relatively,
for the purpose of distributing and continuously
advancing the fuel delivered to the furnace, and

for the purpose of shaking out the resultant ash
during its formation.

The foregoing and such other objects and ad-
vantages as may appear or be pointed out as this
description proceeds are attained in the struc-
tural embodiment illustrated in the accompan-
ying drawings, in which:

Figure 1 is a partial front elevational view,
partly in vertical section, illustrating a furnace
equipped with the present invention;

Figure 2 is a vertical, longitudinal, sectional
view taken generally on the plane of line 2—2, of
Figure 1, looking in the direction indicated by the
arrows;

Figure 3 is an enlarged, transverse, sectional
view of the improved grate bar of this invention;

Figure 4 is a fragmentary, elevational view of
the grate bar;

Figure 5 is a fragmentary, sectional view of a
modified form of the grate bar;

Figure 6 is a fragmentary, elevational view of
the same.

Referring first more particularly to the im-
proved method of stoking a furnace involved in
my co-pending applications S. N. 608,228 now
Patent No. 1,977,620 and S. N. 749,435, there are
included the steps of sizing and depositing con-
tinuously a required quantity of fuel, such as coal
and the like, in a furnace; then the step of con-
tinuously agitating, conveying, and thus distrib-
uting the fuel uniformly throughout the furnace
fire box in order to attain a level fire; and, sim-
ultaneously with such distribution and during con-
sumption of the fuel, removing the ash from the
entire area of the fire bed as such ash is formed,
collecting, and disposing of the resultant ash, thus
maintaining in operation a continuously clean,
ash-free fire. In attaining the various steps
outlined above, I provide a structural arrange-
ment which comprises fuel sizing, measuring
and depositing mechanism, an improved grate
structure, particularly characterized by the pro-
vision of revoluble grate bars, arranged in a single
group or in multiple groups of any desired
lengths, and an improved ash collecting and dis-
posal mechanism adapted to be operated, contin-
uously if desired, with said fuel feeding mech-
anism and grate.

The improved grate bar herein illustrated and
described, while not limited to use with such
structures as shown in my co-pending applica-
tions above referred to, is particularly adaptable
to such use.

Referring first to Figures 3 and 4, which ex-
emplify one form of grate bar, I provide a cylin-

drical shell 5, which is provided with an enlarged axial bore 6, said shell or cylinder 5 being closed by end walls 7, preferably integral therewith. The end walls are provided with polygonal openings 8, and complementally shaped blocks 9 are receivable in said openings. A revoluble shaft 10 is fixedly connected to the blocks 9 and extends axially through the shell 5, which may be made in sections of any desired length and then fixedly secured to shaft 10, said shaft being mounted in suitable bearings 11, arranged as will be more particularly pointed out later.

The cylindrical wall of the shell 5 is provided with radial apertures 12—12, these apertures conveniently being substantially frusto-conical as shown, but they may be of any suitable tapering contour, and having their larger ends presented toward the axis of the shell. The outer portions of the openings 12 are countersunk as at 13—13, so that tapered angularly related shoulders 14—14 are provided thus forming tubes of a general venturi shape. As best seen in Figure 4, the countersunk portions 13 may be substantially square and the apertures of each circumferential series, such as A and B, are complementally disposed in longitudinal rows. The function of this grate bar is to receive the fuel and keep same constantly agitated, at the same time propelling and distributing the fuel over the fire box area, and permitting a free draft through the grate structure at all times. Furthermore, the openings 12 permit the ash, in course of formation, to drop through the grate bar and thus prevent fusing or clogging due to clinkering of the ash on the grate. The shoulders 14—14 serve to provide an uneven abrasive surface on the grate to constantly remove the ash from partially consumed fuel and thus prevent adherence of large particles of fuel and insure complete consumption.

Upon reference to Figures 5 and 6 it will be observed that I have provided a modified form of the grate bar shown in Figures 3 and 4. In this arrangement the shell or cylindrical bar 15 is provided with a wall thicker than that of the cylinder or shell 5, in other words, the bore 16 of 45 less diameter than that of the bore 6. The shell 15 is provided with a plurality of apertures similar to apertures 12 of Figure 4 such as at 17—17, arranged in circumferential series, but in which the apertures of adjoining series, such as C and D, shown in Figure 6, are relatively offset or staggered, so that instead of each unit of adjacent series being in longitudinal rows, the apertures of alternate circumferential series are in a row. 50 This arrangement permits of a finer or closer disposition of the apertures and thus permits of a greater number of draft openings to a bar. However, the grate bar structure shown in Figure 3 will give entirely satisfactory results, and the two bars may be employed in conjunction, as will appear later.

The apertures 17 are of the same shape as the apertures 12 and are provided with countersunk portions 18 at their outer ends. The countersunk portions 18, as best seen in Figure 6, afford tapered shoulders 19, but these shoulders, instead of being right-angularly related as are the shoulders 14, are disposed at relatively acute angles. The securing of the grate bar 15 to its shaft 20 is accomplished in a manner similar to the manner of securing the grate bar 5 to its shaft 10, that is, slidably mounted thereon; and, therefore, need not be described here.

The grate bar structure may embody bars of any desired lengths, and may be assembled in

any desired and suitable manner for accomplishing the end for which the same is designed, but I prefer to assemble this grate bar structure in a mechanical organization to be presently described. However, the desired results may be attained by arranging a plurality of grate bars similar to those just described, in a continuous series, and then providing means for imparting rotation to the grate bars. It is preferable with some fuels that the bars be placed quite closely related and in the same substantially horizontal plane, and if desired, in some instances, the bars may almost touch. However, as the bars all are intended to rotate in the same direction in a given series, it is desirable that some space be afforded between them. It will be observed that by the provision of cylindrical grate bars, the burning surface, or that surface presented toward the fire bed, is materially increased in area, probably to approximately thirty-three and one-third per cent over that which would be afforded by a grate bar having the same width of burning surface as the diameter of the cylindrical bar. For instance, a cylindrical bar six inches in diameter affords a surface one-third greater in area than that of a flat bar six inches wide. This makes the invention very desirable and valuable where great capacity (fuel consumption) is required within a restricted area, such as in locomotive furnaces.

Referring now to a simple installation involving the improved grate bar of this invention, it will be seen upon viewing Figures 1 and 2 that there is provided a furnace structure, which includes a bed or base 21, containing an ash pit 22, accessible through the doors 23, and disposed beneath a grate bar structure, generally designated 24, and constructed in accordance with this invention.

The fire box 25 is provided with the usual end walls 26 and 27, which support water tubes 28. As the boiler structure is not, in detail, essential to this invention, it will be referred to but generally.

The grate structure, as illustrated in Figures 1 and 2, comprises a plurality of the bars 5, hereinbefore described, the shafts 10 of said bars being revolvably mounted in bearings 11—11 above referred to, which latter may conveniently be integrally cast with a supporting base 31 as indicated at 30—30. It will be understood, of course, that two of the supporting bases 31 are provided, one on either end of the grate carrying shaft 10 where this number is sufficient to support the grate, and that, similarly, there are provided two abutments 32, only one of which is shown, affording a carriage for supporting the complementary base members 34. The base member, as shown in Figures 1 and 2, is fixedly secured to the top of the abutment, by the provision of bolts 33, or the like.

The carriage formed by the abutments 32, is mounted on the axles 34 and 35, which are in turn carried by wheels 36 and 37, respectively, said wheels operating on rails 38.

On each of the shafts 10 there are mounted a worm gear 39, said gears meshing with a worm 40 which extends longitudinally of the grate bar structure and above said gears. The worm 40 is rotatably mounted in split bearings 41 and 42, carried by the upstanding brackets 43 and 44, which latter, as seen in Figures 1 and 2, are suitably mounted upon the axles 34 and 35.

The split bearing 41 is provided with a pedestal portion 45, to which is fixedly secured a support

ing bracket member 46. The bracket 46 is provided with a shelf which projects therefrom, and upon said shelf there is fixedly mounted a driving unit, such as a two-cylinder steam engine 48. The shaft 49 of said engine carries a worm 50, which is in meshing engagement with a worm gear 51 fixedly mounted upon an external transverse shaft 52. The shaft 52 carries a worm 53, which is in meshing engagement with a worm gear 54, fixedly mounted on the projecting forward end 55 of the screw or worm 40. It will be seen that as the engine rotates shaft 49, motion is transmitted through the worm 50, gear 51, worm 53, shaft 52 to the worm gear 54, and in turn rotary motion, at a speed, which may be constant or variable, is transmitted to the worm 40. Of course, a variable speed electric motor may be employed, or the engine may be provided with a controlling throttle. The direction of rotation 20 of the worm 40 is such that the grate bars 5 will be rotated in the direction of the arrows E, Figure 2, and thus, fuel which is deposited upon the grate at the forward end, that is, the end near the bearing 41, will be conveyed toward the 25 rear end of the grate structure in the course of consumption.

It is desirable that the ash which does not pass through the perforations in the grate bars or between the grate bars themselves be finally collected at the rear end of the grate and deposited in the ash pit 22, from whence it may be conveyed by suitable mechanism. To this end, the grate structure is provided with an outlet space, which space may be adjustable and is generally 30 designated 56, afforded by spacing two grate bars as shown in Figure 2. In order that the ash which is conveyed to this end of the grate structure, be deposited through the space 56, two or more grate bars 57—57 are arranged beyond the 35 bracket 44, and the portion 58 of the screw or worm 40 which engages and drives said grate bars 57, is relatively reversed to the major portion of the worm 40, and thus the grate bars 57 will be caused to rotate in the direction of the arrows F, thereby affording a mechanical discharge of ash through space 56.

The rollers 63 are adapted to rotate in the direction of the arrow G, Figure 2.

It will be observed that fuel is introduced into a furnace by deposition on a grate structure, the latter being composed of revoluble grate bars, and as these bars are constantly rotated at a desired suitable speed, the fuel, in course of consumption, is carried from one end of the furnace to the other end thereof. As the grate bars are in slight spaced relationship, and as each bar is provided with perforations, the resulting fine ash as formed is therefore constantly removed from the fuel bed and deposited in the ash pit 50 22. The constant agitation of the fuel due to its passage over the uneven surface of the grate bar insures an even distribution of the fuel throughout the furnace and thus affords a level fire in which holes cannot occur. The uneven 55 abrasive surfaces of the grate bars serve to remove the partly consumed fuel from that which is not entirely consumed, and thereby facilitates complete ignition. Furthermore, the larger particles of ash or any fuel which is not entirely consumed, will not pass through the perforations 60 of the grate bars, but will be deposited at one end of the ash pit, from whence it may be retrieved for further use.

A flue 79a is provided at the forward end of the furnace and affords an exit for distilled gases

developed during combustion at that end of the furnace, and the resultant coke (fixed carbon) is conveyed toward the rear end of grate, and may be burned at this location, or thence it is deposited through opening 56, and conveyed to a point of utilization.

The fuel feeding mechanism, represented by the rollers 63, serves to distribute the fuel over the entire width of the grate structure, and thus the fuel is not deposited only in one spot. This is further aided by the provision of the flaring hopper 60.

The grate bar structure may be readily bodily removed by separating the bracket 46 from the front end of the furnace, and running the grate structure out upon the rails 38. A removable wall 38' permits access to the grate in use.

From the foregoing description and the accompanying drawings, it will be observed that there is provided a fuel feeding device or stoker which may be readily adapted to various types of furnaces, and as previously pointed out the provision of the curvilinear grate bar surfaces increases the burning surface of the grate for a given area at least one-third over that ordinarily attained, 25 and at the same time, while revolving, does not vary the distance between the bars, which would occur with flat bars. Furthermore, the features of operation and the functions possible of attainment in this invention permit of employment of the device either as a steam generating plant or as a coking mechanism, or permits of employment of the device both as a steam generating plant and as a coking mechanism. The provision of the outlet 79a shown in Figure 1 permits 30 of the recovery of unburned gases which usually are generated when fuel is first deposited on a fire, and which gases usually pass off and are wasted. An important feature of this invention resides in the function of the grate bars wherein 35 they constantly remove ash as formed, so that not only is the fuel properly sized and distributed to maintain a level fire and thus prevent "holes", but the fire is always maintained free of ash. Thus, for all practical purposes, no clinkers can 40 form. In all cases the revoluble grate bars or groups of revoluble grate bars may be used in a level, horizontal plane as shown or at any desired angle therefrom.

The foregoing features are common to all of 45 the forms of the invention described and will be common to any further modifications which employ the revoluble abrasive grate bars of this invention. These grate bars, being provided with air ducts, afford an even and well distributed 50 area of draft. In fact, by the provision of the flared parts of the draft apertures, best shown in Figures 5 and 6, there is practically one hundred per cent draft area afforded, which further cooperates to prevent the development of cool 55 spots or holes in the fire. This arrangement of the draft openings prevents burning of the grate as plenty of fresh air is always passing through the bars and they are constantly presenting fresh 60 surfaces to the fire bed.

It will be obvious to those skilled in the art that this stocking device is adaptable for use with various kinds of fuel, with any form or method of draft, natural or mechanically produced and conveniently and effectively responsive to any 70 form of regulation, thereby affording a highly efficient and dependable means for carrying out combustion operation, whether for the purpose of producing power, or for use in connection with metallurgical, by-product processes and commer- 75

cial and industrial gas manufacturing. This will be clear when it is seen that the device may be readily employed for pre-treatment of the fuel and that the distillates therefrom may enter into the general combustion, or they may be diverted wholly or in part to other uses as desired.

Having thus described my invention and illustrated its use, what I claim as new and desire to secure by Letters Patent is:

10. 1. A tubular grate bar provided on the outer surface thereof with a plurality of intersecting ridges lying in a cylindrical surface and forming a plurality of polygonal depressions, and radial draft openings through the wall of said grate bar in each of said depressions.
15. 2. A grate structure having a plurality of tubular grate bars mounted for rotation in closely adjacent parallel relationship, said grate bars having an outer surface comprising a plurality of intersecting ridges lying in a cylindrical surface and delimiting depressed areas, and frusto-conical draft openings in each of said depressed areas passing radially through the walls of said tubular grate bars.
20. 3. A grate structure including a tubular grate bar provided with a plurality of radial apertures in the peripheral wall thereof, said apertures being of a tapering configuration and reducing in area from the inner surface of said tubular grate bar toward a point adjacent to the outer surface, whence the walls of said apertures flare to form intersecting abrading ridges on the outer surface of said tubular grate bar which lie entirely in a cylindrical surface.
25. 4. In a grate structure adapted to convey fuel

from an inlet to an outlet in combination, a plurality of tubular grate bars arranged in parallel closely adjacent relation, and each rotatably mounted upon a fixed axis, the outer surface of said grate bars having a plurality of polygonal depressions forming intersecting ridges which lie in a cylindrical surface, said ridges on adjacent bars cooperating to form a substantially continuous surface, and means for continuously rotating said adjacent bars in the same direction.

10. 5. A grate structure comprising a hollow cylindrical member having substantial wall thickness, said wall having a plurality of regularly positioned apertures therethrough, said apertures extending radially through the wall and being 15 frusto-conical and decreasing in cross section from the inner wall surface to an intermediate wall region and thereafter increasing in cross section outwardly as frusto-pyramids to form a 20 series of polygonal depressions on the outer cylindrical surface of the grate.

6. A grate structure comprising a plurality of hollow cylindrical grate bars mounted for rotation in closely adjacent parallel relationship, each grate bar having a substantial wall thickness 25 provided with a plurality of regularly positioned apertures therethrough, said apertures being frusto-conical and decreasing in cross section from the inner wall surface to an intermediate wall region and thereafter extending as frusto- 30 pyramids and increasing in cross section outwardly to form a series of polygonal depressions on the outer cylindrical surface of the grate bar.

FRANCIS H. BROWN. 35
